REFUSE COMPACTOR CABINET

Michael J. Bottas, St. Joseph, Mich., assignor to
Whirlpool Corporation

Filed June 23, 1970, Ser. No. 23,621

Term of patent 3½ years

Int. Cl. D15—99

U.S. Cl. D55—1

FIG.1

FIG.2

FIG. 1 is a perspective view of the refuse compactor cabinet illustrating the design.

FIG. 2 is a fragmentary perspective view of the top front of the cabinet of FIG. 1 but showing the sliding panel at the top of the front of the cabinet on the right-hand side in retracted position to expose the operating controls.

I claim:

The ornamental design for a refuse compactor cabinet, as shown and described.
